UNITED STATES PATENT OFFICE.

ESLE V. MERCER, OF WYANDOTTE, MICHIGAN.

ROLLER WINDOW-SCREEN.

1,202,559.

Specification of Letters Patent. Patented Oct. 24, 1916.

Application filed December 31, 1915. Serial No. 69,592.

To all whom it may concern:

Be it known that I, ESLE V. MERCER, a citizen of the United States, residing at Wyandotte, in the county of Wayne and State of Michigan, have invented certain new and useful Improvements in Roller Window-Screens, of which the following is a specification.

My invention relates to new and useful improvements in window screens, the object of my invention being the provision of a roller window screen and housing of such a nature that they may be permanently attached to the window casing to permit raising and lowering of the screen at will in order that ready access to the windows for the purposes of cleaning them may be had, and furthermore in order that the screen may be wholly inclosed in its housing when actually not needed, in order to protect it from dirt and dampness.

A further object of my invention consists in the provision of a screen of the above described character which is wound upon and unwound from a spring tensioned roller contained in the housing and in this connection I provide a novel means for operatively connecting the tensioning spring to the roller and to its shaft and a means for mounting its shaft or trunnion in the housing in such a manner that it may be manually turned, if necessary, without removing the roller from the housing to permit varying of the tension of the spring. In this connection, with the above described spring roller, housing and screen, my invention further comprehends the provision of simple and effective guides constructed in a novel manner from strips of sheet metal pressed to suitable shape and secured to the outer sash strips of the window casing to receive, guide and support the lateral edges of the screen itself, the upper ends of these strips extending into the housing and supporting and directing the screen toward the roller.

A still further object of my invention consists in the provision of a novel form of bottom bar for the screen which serves to protect the lower free edge of the screen when it is extended, as a stop for limiting

the winding of the screen upon the roller when the screen is released and as a handle for moving the screen to any desired position. I also provide a lock engageable with this bar when the screen is in fully extended position to hold the screen against the tension of the spring.

With these and other objects in view, my invention will be more fully described, illustrated in the accompanying drawings, and then specifically pointed out in the claims which are attached to and form a part of this application.

In the drawings: Figure 1 is a fragmentary perspective view of the exterior of a building, showing my improved roller screen structure applied to a conventional form of window casing; Fig. 2 is a central vertical sectional view taken through the casing, screen housing and screen, showing the screen in partially extended position; Fig. 3 is a vertical sectional view taken diametrically of the roller, showing certain details of housing and roller construction, the screen being omitted from the roller to render the disclosure more clear; Fig. 4 is a fragmentary vertical sectional view taken on the line 4—4 of Fig. 3, illustrating the manner of connecting one end of the screen to its roller; Fig. 5 is a corresponding sectional view taken on the line 5—5 of Fig. 3, illustrating the manner of connecting the spring to the roller and to its shaft or trunnion; Fig. 6 is an elevational view of the spring inclosing end of the casing, showing the spring roller or trunnion in section to disclose the manner in which it is mounted in the casing; Fig. 7 is a fragmentary transverse sectional view taken on the line 7—7 of Fig. 2, illustrating the construction of the guides for the lateral edges of the screen; Fig. 8 is a fragmentary vertical sectional view taken through the lower edge of the screen and illustrating the manner in which the bottom bar or strip is connected to it.

Corresponding and like parts are referred to in the following description and indicated in all the views of the drawings by the same reference characters.

The preferred embodiment of my invention, as disclosed in the drawings, com-

hends the provision of a casing, generally formed of sheet metal, adapted to be secured to the upper outer portion of any conventional type of window casing and carrying a spring roller to which is connected one end of a screen which may be drawn from the housing to extend the entire length of the window casing or over any desired portion thereof and any suitable arrangement of guides at the sides of the window casing to receive the lateral edges of the screen.

More specifically, I provide a housing, indicated as a whole by the numeral 10 and including end walls 11 and 12 which, at their inner ends, are provided with laterally directed flanges 13 for engagement against the outer faces of the outer sash strips or rails 14 of the window casing 15. These flanges are perforated to receive screws 16 or other suitable fastening devices by means of which the end walls are mounted in place at the upper end of the window casing. The upper and lower edges of these end walls are provided with outwardly directed ears 17 formed just outside of the window casing and with their outer faces in the planes of the respective edges of the end walls. The free ends of the end walls are rounded or semi-circular in shape, as clearly shown to conform to the inner face of the body portion proper 18 of the housing 10. This body portion proper 18 of the housing is substantially U-shaped in section, its intermediate portion engaging about the extended portions of the end walls and its side portions projecting in spaced relation to the sash strip 14 of the window casing, in the manner shown in Fig. 4. The ends of the housing proper 18 extend slightly beyond the end walls and are apertured to receive bolts 19 which are passed through the ears 17 of the end walls and the housing and secured by nuts 20. The end wall 11 is formed centrally with an opening forming a bearing for one trunnion of the roller, as will be later explained and the other end wall 12 is formed with an inwardly and downwardly extending slot 21 to receive the other trunnion of the roller, the inner end of this slot being in alignment with the opening in the opposite end wall and the slot adjacent such inner end being widened, as shown at 22. Mounted within this housing is the roller, indicated as a whole by the numeral 23. This roller includes two heads 24 and 25 constituting its ends and a tubular body 26 connected at its ends to the heads. The head 24 is in the form of a disk provided centrally with a stud or trunnion 27 which revolvably seats in the opening in the end wall 11 and formed upon its opposite or inner face with an annular flange 28 concentric to the trunnion 27 and seating in the connected end of the body 26 of the roller. The head 27 includes a circular body portion

of such diameter as to seat within the connected end of the roller body 26 and formed with an outwardly directed annular flange 29 which, beyond the end of the roller, is formed with a peripheral flange 30 engaging the inner face of the end wall 12 of the housing. This head 25 is also formed centrally with an outwardly directed hub portion 31. The flanges 28 and 29 of the heads are provided at spaced intervals with shallow recesses or sockets and those portions of the roller ends overlying the sockets are struck, as shown at 32 by means of which the heads are permanently connected to the ends of the roller.

Corresponding to the trunnion 27 is a bolt 33 which is passed inwardly through the slot 21 of the end wall 12 of the housing and through the hub of the head 25, the shank of the bolt adjacent its head which engages against the end wall being squared to seat in the slot 21 and thus be held against turning movement unless the roller as a whole is tilted to bring the shank portion of the bolt into engagement with the enlarged portion of the slot. That portion of the bolt shank extending beyond the head 25 is formed with a slot 34 and one end of a spiral spring 35 is seated in the inner end of this slot, as best shown at 36 in Fig. 5. The opposite end of the spring 35 is formed with an eye 37 to engage about an inwardly directed pin 38 extending from the head 25 adjacent its peripheral edge. A washer 39 is mounted upon the inner end of the bolt to engage against and house in the spring and a nut 40 is threaded upon the bolt to hold the washer in place and so prevent displacement of the spring from the bolt and pin 38. By means of this, it will be seen that one end of the spring is connected to one of the heads of the roller and the opposite end of the spring connected to the fixed trunnion formed by the bolt 33.

The body 26 of the roller 23 is preferably formed of relatively heavy sheet metal bent into cylindrical shape and with its overlapping edges soldered or otherwise secured, as shown at 41 in Fig. 4. The outer or overlapping edge of this body is, however, preferably extended beyond the point of attachment to the edge which it overlaps and is rebent upon itself to form a hook 42 extending the entire length of the roller. The screen 43, co-acting with the above described roller, is, of course, formed of any suitable metal and has its upper edge bent upon itself, as shown at 44, to seat beneath the hooked edge 42 of the roller. By this means, the roller and screen are detachably secured to each other without the necessity of any fastening devices whatsoever, it of course being understood that the screen is preferably of such length that there will always be sufficient of the wire netting wound about

the roller to prevent its displacement, even when the screen is drawn to fully extended position.

The strip of wire netting forming the screen 43 is of course equal in width to the width of the window casing to which it is applied and its lateral edges extend into and are supported and guided by guideways 45 secured to the window casing. The construction and manner of mounting these guideways 45 may be best understood from the transverse sectional view shown in Fig. 7. Each of these guideways is formed from a single strip of sheet metal, substantially equal in length to the length of the window casing and bent to provide the U-shaped body 46. One of the longitudinal edges of this body is outwardly bent upon itself, as shown at 47, to reinforce the strip and also to present a smooth and neat appearance and the opposite edge of the strip is correspondingly rebent upon the body to a point intermediate the length of the side of the body at which point it is outbent to extend at right angles to the body, as shown at 48. This outbent portion 48 of the strip forms in effect an attaching flange and seats against the inner edge of the sash strip 14 to which it is secured by screws or other suitable fastening devices 49. By this means, the guideways 45 are secured to the sides of the window casing to extend vertically just in front of the sash strips 14 with their open edges directed toward each other to receive the lateral edges of the screen 43.

The lower or free end of the strip of netting forming the screen 43 is bound in, protected and reinforced by a bottom bar structure, indicated as a whole by the numeral 50 and best illustrated in Fig. 8 of the drawings. This bottom bar includes two members 51 and 52 each formed from a single strip of sheet metal substantially equal in length to the width of the window. The member 51 is bent in such a manner that it is U-shaped in section with one free edge extending but a slight distance with respect to the other. The other free edge is rebent upon one side of the body portion, as shown at 53 to a point opposite the intermediate portion and then outbent, as shown at 54, to extend at right angles to the doubled side portion of the strip, the free edge of such outbent portion being doubled under, as shown at 55 to present a neat and finished appearance and to strengthen the strip as a whole.

Co-acting with the above strip is the strip 52 which is bent to provide a body portion U-shaped in cross section, as shown at 56, with one side projecting beyond the other and outbent, as at 57, to correspond to the outbent portion 54 of the other strip, this outbent portion being doubled under upon

itself, as shown at 58. These strips forming the reinforcing bar 50 are connected to each other and to the free edge of the strip of netting forming the screen by rebending the free edge of the netting, as shown at 59 and 79 seating such rebent edge of the netting between the side portions of the body of the strip 51. The free side portion of the strip 52 is then inserted between the body of the strip of netting and its rebent terminal to 75 clamp the netting in place, the interlocking portions of the two metal strips and the netting all frictionally engaging each other. If necessary, pressure may be exerted against the outer faces of the strips 51 and 52 to render this engagement closer and in any event a screw 60 is preferably passed through the intermediate portions of the bar forming strips and secured by a thumb nut 61 which may form a handle for grasping the bar and which also, of course, prevents any independent movement of the netting and strips forming the bar. The outwardly directed edges or flanges 54 and 57 of the bar form a base for the screen which may engage flatly against the sill 62 of the window casing when the screen is fully extended. As a means for securing the screen in extended position, against the tension of the spring 35, I attach a plate 63 to the central portion of the sill 62. This plate carries a turn button 64 which may be swung over the inner flange 57 of the bottom bar 50 when the screen is in fully extended position to hold it in place. As shown in Fig. 2 of the drawings, the lower wall of the housing 10 extends nearly to the guide strips 45 and any possibility of the bar 50 being drawn up into the housing, upon release of the screen, is prevented as its flange 54 will engage the bottom wall of the housing and so limit its upward movement. Of course, as will be appreciated by reference to Fig. 7 of the drawings, the outwardly directed flanges 54 and 57 of the bottom bar are cut away at their ends in order that the ends of the bar itself may extend into the guideways 45.

In applying the screen, constructed in accordance with my invention, the end walls are secured in place, the roller positioned between the end walls with the screen attached, the guideways positioned in place, and the lower end of the screen inserted in the upper ends of the guideways. The roller may then be tested by drawing the screen to extended position to see if the spring is properly adjusted. If the spring is too tight or too loose, the roller may be tilted somewhat to bring the trunnion forming bolt 33 into the enlarged portion 22 of the slot when the spring may be properly adjusted by turning the bolt, after which the bolt is again moved into the inner end of the slot and so held against turning movement. 125 130 135

When the roller has been properly adjusted in this manner, the body portion proper of the casing is put in position and secured to the end walls as previously described.

5 From the foregoing description of the construction and application of my improved roller screen for windows, it is believed that the manner of its employment will be readily understood and that any further explanation is unnecessary.

Although I have illustrated and described my invention in all its details of construction, it will be obvious that various conditions concurrent with its manufacture and 15 application may necessitate certain minor changes in construction and design and I reserve the right to make any alterations within the scope of the appended claims.

Having thus described the invention, 20 what is claimed as new is:

1. A roller window screen including a housing having end walls, one formed with a trunnion receiving opening and the other with a trunnion receiving slot, a roller in 25 the housing having heads, one formed with a trunnion to seat in the opening of the adjacent end wall of the housing and the other formed with a central opening, a bolt extending through the opening and having 30 a squared shank portion adjacent its head seating in the slot of the other end wall of the housing, the free end of the shank portion of the bolt being provided with a longitudinal slot, a stud projecting from the 35 head through which the bolt extends in spaced relation to the bolt, a spiral spring wound about the bolt with its inner end seated in the slot of the bolt and its outer end looped about the stud, a washer passed 40 over the bolt and with the head forming a housing for the spring, means for preventing displacement of the washer, and a screen 45 properly secured at one end to the roller and wound thereabout.

2. A roller window screen including a spring roller, netting wound about the roller and adapted to be unwound therefrom, and a housing adapted to operatively receive the roller and to be positioned at the top of a 50 window casing, said housing including end walls adapted to form bearings for the roller and provided at their inner edges with lateral flanges for attachment to the sash strips of the window casing and with outwardly 55 directed ears, the outer ends of the walls being substantially semi-circular, a U-shaped body portion proportioned to snugly engage about the end walls and to project in spaced relation at its free edge to the sash strips, such body portion being of such length as to 60 extend slightly beyond the end walls and engage the ears, and fastening devices passed through the body and ears.

3. A roller window screen including a

housing having end walls, one formed with a 65 trunnion receiving bearing and the other with a downwardly and inwardly extending trunnion receiving slot enlarged adjacent its inner end, a spring roller mounted in the housing and having a trunnion at one end 70 seating in the opening of one end of the housing and a spring carried trunnion in its opposite end having a squared portion engageable in the slot and held against turning therein but free to turn when swung into the 75 enlarged portion of the slot, and a screen secured at one end to the roller and adapted to be wound thereon and unwound therefrom.

4. A roller window screen including a 80 housing adapted to be secured to a window casing, a spring roller mounted in the housing, a strip of screening connected at one end to the roller, and a brace bar secured to the other end of the strip, the brace bar including co-acting U-shaped body portions, the free end of the screen strip being rebent upon itself to seat between the sides of one body portion and being wedged therein by the insertion of one side of the other body 90 portion between it and its rebent portion, both body portions being formed with oppositely directed flanges lying in a common plane to form a sill engaging base.

5. A roller window screen including a 95 housing adapted to be secured to a window casing, a spring roller mounted in the housing, a strip of screening connected at one end to the roller, and a brace bar secured to the other end of the strip, the brace bar including co-acting U-shaped body portions, the free end of the screen strip being rebent upon itself to seat between the sides of one body portion and being wedged therein by the insertion of one side of the other body 100 portion between it and its rebent portion, both body portions being formed with oppositely directed flanges lying in a common plane to form a sill engaging base, and a bolt passed through the sides of the body, the 110 screen and its rebent terminal to bind all together.

6. A roller window screen including a housing, a spring roller mounted in the housing, a strip of netting secured at one 115 end to the roller and extensible therefrom, and guideways adapted for attachment to the sides of a window casing to receive and support the lateral edges of the netting, said guideways including U-shaped body 120 portions adapted to receive the edges of the netting between their sides and laterally directed flanges projecting from the intermediate portions of one side of the body portions and adapted for attachment to the sash 125 strips of the window.

7. A roller window screen including a housing having end walls, one formed with

a trunnion receiving opening and the other with a trunnion receiving slot, a roller in the housing having heads, one formed with a trunnion to seat in the opening of the adjacent end wall of the housing and the other formed with a central opening, a bolt extending through the opening and having a squared shank portion adjacent its head seating in the slot of the other end wall of the housing,

the free end of the shank portion of the bolt 10 being provided with a longitudinal slot, a spiral spring wound about the bolt with its inner end seated in the slot thereof and its outer end anchored to the head, and means for preventing movement of the spring longitudinally of the bolt.

In testimony whereof, I affix my signature.
ESLE V. MERCER. [L. S.]
